UNITED STATES PATENT OFFICE.

HARRY F. HALL, OF PHILADELPHIA, PENNSYLVANIA.

EXPANSIBLE PULLEY.

SPECIFICATION forming part of Letters Patent No. 431,889, dated July 8, 1890.

Application filed March 4, 1890. Serial No. 342,565. (No model.)

To all whom it may concern:

Be it known that I, HARRY F. HALL, a citizen of the United States, residing in the city and county of Philadelphia, State of Pennsylvania, have invented a new and useful Improvement in Expansible Wheels or Pulleys, which improvement is fully set forth in the following specification and accompanying drawings.

10 My invention relates to improvements in expansible wheels or pulleys; and it consists of a wheel or pulley having an inclined side and provided with a sleeve having pivoted arms with heads, the latter adapted to move 15 in radial lines on said inclined side.

It further consists of the combination of parts herein set forth.

Figure 1 represents a side view of a device embodying my invention. Fig. 2 represents 20 a plan view of the device shown in Fig. 1, the top of one of the ways of a sliding arm being broken away. Fig. 3 represents a vertical section on line $x-x$, Fig. 2. Fig. 4 represents a vertical sectional view on line $y-y$, Fig. 2. Fig. 25 5 represents a perspective view of one of the pivoted arms with head and block.

Similar letters of reference indicate corresponding parts in the several figures.

Referring to the drawings, A designates an 30 expansible pulley secured on the shaft B, the latter being suitably journaled in the standards C. One side of the pulley is beveled or inclined from the hub D to the periphery E, and in the same are formed the grooves F, 35 extending radially to the periphery and of dovetail form. A sleeve G is keyed to the shaft B, so as to rotate therewith and have a lateral movement thereon. Embracing the sleeve G is a yoke H, provided with two laterally-extending arms J, the ends of which 40 move in ways or guides K, supported by the standards L. To one end of the sleeve G is pivotally secured the radially-extending arms M, which carry the hinged or pivoted heads N, having the grooves P thereon. A dovetail block Q is connected with each of the heads N, and is fitted in a radial groove F, so as to 45 be adapted to slide therein, the side of the block Q adjacent to the grooved head N being inclined and flush with the side of the pulley A.

To move the arms J in the ways K, the following described mechanism is employed: A rotary shaft R, which is journaled in the standards S, has mounted thereon two bevel gear-wheels T T, which mesh, respectively, with two bevel gear-wheels U U, secured on the rotary screw-rods V V. The said rods V V are journaled in bearings on the standards L, and the screw-threaded parts thereof work 60 in the nuts W, which are located in the slots or recesses X in the arms J.

Power may be communicated to the pulley A in any suitable manner. In the mechanism shown in the drawings a grooved driving-pulley Y is connected with the sliding heads N of the expansible pulley A by the ropes Z, the said pulley Y being mounted on a shaft A', which is rotated by means of the gear-wheels B' and C', the latter mounted on a shaft D' 70 and provided with a crank-handle E'.

A tension device for taking up the slack of the ropes Z consists of a grooved drum or pulley loosely mounted on a shaft F', the latter having the sliding bearings G', adapted to 75 rise and fall on ways on the uprights H'.

The manner of operating the device is as follows: Power having been communicated to the pulley A from the driving-shaft A' by means of the pulley Y and ropes Z, if it be 80 desired to change the speed of the said pulley A and its shaft the shaft R is rotated by means of the driving-wheel J', with crank-arm thereon, on the said shaft, so that the bevel-gears T T, meshing with the bevel-gears 85 U U, rotate the screw-rods V V, thereby moving the nuts W endwise on the said rods, and thus moving the arms J on the guides or ways K. This motion of the arms J causes the yoke H and sleeve G to slide on the shaft B, so 90 that the ends of the radial arms M, pivoted to said sleeve, either recede from or approach toward the hub of the pulley A, according to the direction of the rotation of the wheel J'. If the sleeve G is approaching the 95 hub D, the heads N will be forced or moved outward toward the periphery of the pulley, thus increasing the diameter of the part thereof which receives power from the driving-pulley, and thereby decreasing the speed 100 of the pulley A and its shaft. If the sleeve D recedes from the hub, the effect is to di-

minish or lessen the diameter of the part of the pulley directly connected with the driving-pulley, and thereby increase the speed of the shaft of the expansible pulley.

5. By the mechanism herein described the speed of any machine can be readily changed, either increased or diminished, without stopping the machine or of shifting belts from one pulley to another.

10. Having thus described my invention, what I claim as new, and desire to secure by Letters Patent, is—

1. The combination of a shaft, a pulley, a series of heads connected with and movable 15 on said pulley and adapted to carry bands thereon, a sleeve on said shaft, arms connected with said sleeve and heads, a yoke with laterally-extending arms, and screws connected with each of said arms for simultaneously 20 moving said arms, substantially as described.

2. The combination of a pulley having grooves in one of its sides, a movable sleeve, and arms pivotally connected with said sleeve and carrying grooved heads to receive a belt 25 and provided with blocks, the latter being pivotally attached to said heads and moving in said grooves of the side of the pulley, said parts being combined substantially as described.

30. 3. The combination of a pulley having radial grooves in one of its sides, a sleeve with arms pivoted thereto and carrying pivoted heads with grooved outer faces to receive a belt, said heads having blocks pivotally connected therewith and movable in the said 35 grooves of the pulley, and mechanism, substantially as described, for moving said sleeve to and from said pulley, substantially as and for the purpose set forth.

40. 4. The combination of a pulley having radial grooves on one of its sides, a sleeve with arms pivoted thereto, heads having grooved outer faces to receive a belt and pivotally connected with said arms and provided with 45 blocks movable in said grooves, a yoke embracing said sleeve and having laterally-projecting arms, and rotative screws, substantially as described, connected with said arms and adapted to move the same simultaneously either to or from the pulley, substantially as and for the purpose set forth.

50. 5. The combination of a pulley having radial grooves in an inclined or beveled side thereof, a sleeve with arms pivoted thereto, heads pivoted to said arms and having blocks guided in said radial grooves, a rotary shaft on which said pulley and sleeve are keyed, and rotative screws, substantially as described, connected with said sleeve for mov-

ing the same either to or from the pulley, substantially as and for the purpose set forth. 6c

6. The combination of a shaft, a pulley and a sleeve on said shaft, arms pivotally connected to said sleeve and provided at their outer ends with pivoted heads, and a rotative 65 screw, substantially as described, for moving said sleeve either to or from said pulley, the said heads being adapted to move on radial lines of said pulley and in contact therewith, substantially as and for the purpose set forth. 7c

7. The combination of a pulley having a grooved side, a sleeve with pivoted arms and heads thereto, a yoke embracing said sleeve and having laterally-projecting arms, guides for said arms, rotary screw-rods adapted to 7: move said arms, and a rotary shaft with bevel-gearing meshing with bevel-gearing on said rotary screw-rods, substantially as described.

8. The combination of a pulley with an inclined side, having radial grooves therein, a 8 sleeve with arms pivoted thereto, heads pivoted to said arms and provided with blocks secured thereto and movable in said grooves, a shaft on which said pulley and sleeve are keyed, a yoke embracing said sleeve and having laterally-projecting arms, ways in which 8 said arms are guided, rotary screw-rods passing through nuts located in slots in said arms, bevel gear-wheels on said rods, and a rotary shaft having bevel-gearing meshing with the 9 bevel-gearing on said screw-rods, substantially as and for the purpose set forth.

9. A pulley with an inclined or beveled side, a sleeve with pivoted arms, a shaft on which 1 said pulley and sleeve are keyed, heads pivoted to said arms and in contact with said inclined side and adapted to move in radial lines thereon, and mechanism, substantially as described, connected with said sleeve for moving the same either to or from the pulley, 1 said parts being combined substantially as and for the purpose set forth.

10. A pulley with an inclined or beveled side and having radial grooves therein, a 1 sleeve with arms pivoted thereto, a shaft on 1 which said pulley and sleeve are keyed, heads pivoted to said arms and having means connected therewith for moving in the line of 1 said radial grooves, a yoke embracing said sleeve and having projecting arms, and mechanism, substantially as described, for moving said arms simultaneously either to or from the pulley, said parts being combined substantially as described. 1
